[57] CLAIM

The ornamental design for a grille cap for a vehicle, as
shown and described.

DESCRIPTION

FIG. 1 is a front perspective view of a grille cap showing
my new design;

FIG. 2 is an enlarged rear elevational view thereof;

FIG. 3 is an enlarged left side elevational view thereof;

FIG. 4 is an enlarged right side elevational view
thereof;

FIG. 5 is an enlarged top plan view thereof;

FIG. 6 is an enlarged bottom plan view thereof;

FIG. 7 is an enlarged sectional view thereof taken along
line 7—7 in FIG. 2.

The broken line showing of a vehicle is for illustrative
purposes only and forms no part of the claimed design.
